(57) **CLAIM**

The ornamental design for a fuel station canopy, as shown and described.

DESCRIPTION

FIG. 1 is a left side elevational view of the fuel station canopy showing our new design with associated environment; FIG. 2 is a front perspective view from the left of the fuel station canopy of FIG. 1;

FIG. 3 is a rear perspective view from the right of the fuel station canopy of FIGS. 1 and 2;

FIG. 4 is a left side elevational view of the fuel station canopy of FIGS. 1-3;

FIG. 5 is a front elevational view of the fuel station canopy of FIGS. 1-4;

FIG. 6 is a right side elevational view of the fuel station canopy of FIGS. 1-5;

FIG. 7 is a rear elevational view of the fuel station canopy of FIGS. 1-6; and,

FIG. 8 is a top plan view of the fuel station canopy of FIGS. 1-7.

The broken line showing is included for the purpose of illustrating environment and forms no part of the claimed design.
